US0D1100222S

(12) **United States Design Patent** (10) **Patent No.:** **US D1,100,222 S**
(45) **Date of Patent:** **** Oct. 28, 2025**

(54) **NECK BRACE**

(71) Applicant: **TARDIS TECHNOLOGY LIMITED,**
Hong Kong (CN)

(72) Inventor: **Zheng Xue**, Baoji (CN)

(73) Assignee: **TARDIS TECHNOLOGY LIMITED,**
Hong Kong (CN)

(**) Term: **15 Years**

(21) Appl. No.: **29/985,167**

(22) Filed: **Jan. 16, 2025**

(51) LOC (15) Cl. **24-04**

(52) U.S. Cl.
USPC **D24/191**

(57) **CLAIM**

The ornamental design for a neck brace, as shown and described.

DESCRIPTION

FIG. 1 is a front perspective view of a neck brace, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the drawings depict elements on the neck brace that form no part of the claimed design.

1 Claim, 8 Drawing Sheets
